United States Patent

Dec. 240,277
Patented June 8, 1976

240,277

CAUTERY

David E. Staub, Clearwater, Fla., assignee to
Concept, Inc.

Filed July 12, 1974, Ser. No. 488,151

Term of patent 14 years

Int. Cl. D24—02

U.S. CL. D63—12 R

FIG. 1 is a front elevational view of a cautery showing my new design;

FIG. 2 is a side elevational view of the cautery illustrated in FIG. 1 with the opposite side being substantially a mirror image thereof;

FIG. 3 is a rear end view of the cautery illustrated in FIG. 1; and

FIG. 4 is a front end view of the cautery illustrated in FIG. 1.

I claim:

The ornamental design for a cautery, substantially as shown.
